Inventor.

James H. Thomas

United States Patent Office.

JAMES H. THOMAS, OF LYNN, MASSACHUSETTS.

Letters Patent No. 79,876, dated July 14, 1868.

IMPROVED WEATHER-STRIP.

The Schedule referred to in these Letters Patent and making part of the same.

TO ALL WHOM IT MAY CONCERN:

Be it known that I, JAMES H. THOMAS, of Lynn, in the county of Essex, and State of Massachusetts, have invented certain new and useful Improvements in Weather-Strips for Doors; and I do hereby declare that the following is a full and exact description thereof, reference being had to the accompanying drawings, and to the letters of reference marked thereon.

To enable others skilled in the art to make and use my invention, I will proceed to describe its nature, construction, and use.

The nature of my invention consists in combining with the lower side of a door a compound flexible roll of peculiar construction, said roll consisting of an outside tube made of some elastic gum, in the interior of which are placed a number of short metallic cylinders, loosely hung upon a centre spindle, so that the entire roll is free to bend, and thus to accommodate itself to the irregularities of the threshold.

Drawings.

Figure 1 is a perspective view, showing a door partly open, with my improved strip attached.

Figure 2 is a longitudinal section.

Figure 3 is a perspective view of the roll or strip.

I construct my roll as follows: D is a tube, made of some suitable elastic gum, in the interior of which are placed a series of short metallic cylinders, K K' K'', &c. These cylinders serve to give weight and stability to the roll, but still, as they are disconnected from each other, do not interfere with the flexibility of the roll; that is, it may bend and accommodate itself to any irregularities in the threshold.

H H is a rod of much smaller diameter than the interior diameter of the metallic cylinders, which passes through the roll or strip, as shown in fig. 2. The ends of the rod H may be bent up, as shown, and thus made fast to the door, or the ends may be confined by plates made fast to the edges of the door.

From the above description it will be seen that my roller, made by inserting into an elastic tube a series of short, heavy cylinders, has weight and stability, and is yet so flexible and elastic that it will serve as a weather-strip, and as it is free to revolve, it will not wear away and become inefficient.

Having thus described my invention, I will now proceed to set forth my claim.

What I claim as my invention, and desire to secure by Letters Patent, is—

The combination of the flexible elastic roll D, with the short cylinders K K' K'', &c., and the spindle H, arranged substantially as described, and for the purpose set forth.

JAMES H. THOMAS.
